Attorney

UNITED STATES PATENT OFFICE

FORD M. WILSON, OF LIBERAL, KANSAS, ASSIGNOR OF ONE-HALF TO HENRY E. SNYDER, OF LIBERAL, KANSAS

WRENCH

Application filed May 28, 1929. Serial No. 366,663.

This invention relates to an improved wrench of the species referred to in the art as a quick adjustable wrench, wherein the movable jaw is slidably arranged on the handle forming shank and regulated or adjusted by quick acting retaining means.

My object is to generally improve upon wrenches of this class by providing one which is characterized by a novel movable jaw construction, and carrier or retaining means therefor.

In carrying the invention into effect, I have evolved and produced an improved assembly of parts forming the movable jaw units, wherein the parts are themselves novel and cooperable in a distinctly new manner, for providing a structure which is expeditiously operable and quick and dependable in action.

The specific elements and their cooperation will become more readily apparent from the following detailed description and the accompanying drawings.

In the accompanying drawings, wherein like reference characters are employed to designate like parts throughout the same:

Figure 1 is a side elevational view showing the handle construction and the adjustable movable jaw unit.

Figure 2 is a horizontal section, taken approximately upon the plane of the line 2-2 of Figure 1.

Figure 3 is a side view of the movable jaw element per se.

Referring now to the drawings, by reference numerals, it will be observed that 4 designates the shank which has the right angularly disposed fixed tooth equipped jaw 5, at its outer end. This is the stationary jaw. Along one edge of the shank at a predetermined point, are retaining teeth constituting a rack 6. The movable jaw unit, generally designated by the reference character 7 is slidable on the shank and cooperable with the rack. This unit comprises a mounting which includes the sleeve portion 8, embracing the shank and a sheath portion 9, which projects outwardly in substantial parallelism with the jaw 5. Arranged in this sheath is a flat spring 10, bearing against one edge 50 of a substantially wedge shaped pawl 11

which is loosely disposed in said sheath. This pawl has its apex portion equipped with a laterally directed keeper 12, which cooperates directly with the rack 6. This keeper of course is formed with teeth, which cooperate with the teeth on the rack. The reference character 13 designates a pivot which connects the pawl with an operating yoke 14. This is of U-shaped form and the arms embrace the shank. The lower end of the outer wall of the sheath 9 is provided with a curved thumb hook 15 which is disposed in opposed relation to the yoke 14. The body portion of the pawl extends through and beyond the sheath where it is provided with an enlarged head 16 having work engaging teeth.

This constitutes the movable jaw per se. Then, there is a coil spring 17 which has one end seated in a socket in the pawl to tip the teeth into engagement with the rack 6 and the opposite end bearing against the sleeve 8.

With this arrangement, it is obvious that the entire unit 7 may be longitudinally shifted toward and from the jaw 5 by simply pressing against the finger yoke 14. This will disengage the teeth of the keeper 12 from the rack teeth 6, and the desired resiliency and pivotal motion is provided to facilitate this disengagement and reengagement. Thus a novel quickly adjustable wrench is provided.

It is evident from the description and drawings that I have described and produced a simplified and economical type of wrench which has been previously unequalled in the art, and which is practical and dependable in accomplishing the requirements of a tool of this class. Persons skilled in the art to which the invention relates, however, will be able to obtain a clear understanding of the same by considering the description and drawings together. Therefore, a more lengthy description is believed to be unnecessary.

Minor changes in the shape, size, materials, and rearrangement of details coming within the field of invention claimed may be resorted to, in actual practice, if desired.

I claim:

In a wrench of the class described, a shank having a longitudinal rack on one edge and provided at its outer end with a right angu-

larly disposed stationary jaw, a movable jaw unit slideable on said shank and comprising a mounting including a sleeve portion snugly embracing and slideable on said shank, and a sheath projecting outwardly in substantial parallelism with said stationary jaw, a pawl loosely disposed in said sheath having its upper end projecting beyond the upper end of the sheath and formed into a toothed jaw and having its lower end projecting below the corresponding end of the sheath, directed laterally and formed with teeth for engaging the rack teeth, spring means in said sheath acting on said pawl to tip said teeth into engagement with said rack, an operating element for the pawl embracing the shank, the operating element comprising a yoke, and a thumb hook depending from the outer wall of the sheath in opposed relation to the yoke to facilitate operation of said elements.

In testimony whereof I affix my signature.
FORD M. WILSON.
